(57) **CLAIM**

The ornamental design for a mount for electronic devices, as shown and described.

DESCRIPTION

FIG. 1 is a front, side, and top perspective view of a mount for electronic devices embodying the new design.

FIG. 2 is a back, side, and bottom perspective view thereof.

FIG. 3 is a front view thereof.

FIG. 4 is a back view thereof.

FIG. 5 is a bottom view thereof.

FIG. 6 is a top view thereof; and,

FIG. 7 is a first side view thereof, the second side view being a mirror image.

The dot-dash lines form an unclaimed boundary of the claim. The dot-dash lines form no part of the claimed design.
